UNITED STATES PATENT OFFICE

JOHN MOOSHERR, OF NEW YORK, N. Y.

DESIGN FOR LACE

Application filed February 5, 1931. Serial No. 38,559. Term of patent 3½ years.

To all whom it may concern:

Be it known that I, JOHN MOOSHERR, a citizen of the United States, residing at 340 East 207th Street, New York city, State of New York, have invented a new, original, and ornamental Design for Lace, of which the following is a specification, reference being had to the accompanying drawing, forming part hereof.

The figure of the drawing is a face view of a piece or section of lace showing my design.

I claim:

The ornamental design for lace substantially as shown.

JOHN MOOSHERR.
